PAPER TRIMMER

Hugh E. Simonton, Memphis, Tenn.

Application May 20, 1931. Serial No. 538,655

1 Claim. (Cl. 164—77)

This invention relates to improvements in paper cutters and particularly to a tool for trimming wall paper, which is designed to run upon and be guided by a straight edge and which employs a rotating disc as the cutting element.

The objects of this invention are:—

To provide a tool which is simple in construction and efficient in action; which may be operated with either hand and in either direction and which is so constructed that the pressure necessary to bring the cutting knife into cutting proximity to the paper is evenly distributed on the straight edge and assists in holding the straight edge in place.

15 A further object is to so construct the tool that the center of pressure in operating the tool lies within the transverse limits of the straight edge whereby the pressures exerted act directly downward on the straight edge rather than with an overturning effect.

20 The means by which the foregoing and other objects are accomplished and the manner of their accomplishment, will readily be understood from the following specification on reference to the 25 accompanying drawing, in which:—

Fig. 1 is a side elevation of the tool with a portion of the case broken away to disclose the interior thereof.

Fig. 2 is a similar view with the cover plate 30 and cutting knife removed and with a portion of the straight edge in section on the line II—II of Fig. 3.

Fig. 3 is a sectional elevation of the tool taken on the line III—III of Fig. 1.

35 Referring now to the drawing in which the various parts are indicated by numerals, the straight edge comprises an elongated strip of sheet metal 10, having its forward edge 11 turned upward at right angles, and thence inward to 40 form a roller support and guide 12 parallel to the base. If desired, longitudinal ribs 13 may project slightly below the bottom of the part 10. 45 14 is an elongated strip, preferably of wood which may be used if desired in connection with the metal straight edge in which case the metal would be secured to the wood in any desired manner.

The cutting tool comprises a handle made up of a casing 15 and a cover 16 which are secured together as by screws 17. The casing 15 is hollowed out and has a forwardly projecting boss 18 positioned at the longitudinal center of the casing, which boss carries a ball bearing 19, on which a sharpened cutting disk or knife 20 is 55 revolvably mounted. The bearing 19 is held in

place by a post 21, the inner end of which is threaded and screwed into the boss 18. The cover 16 has a forwardly projecting hub 22 which is bored out to embrace the post 21. Disposed within the hollowed out portion of the case 15 60 and projecting forwardly from the back thereof are pins 23, 24 which carry a flat spring 25. 26 are arms pivotally mounted on pins 27 which are symmetrically disposed with relation to the boss 18 and which project forwardly from the 65 back of the casing. These arms extend longitudinally away from the boss 18, and each carries at its free end a roller 28. The spring 25 is disposed over the post 23 and under the pins 24 and by these latter pins is held down against the 70 arms 26. All of these parts are disposed behind the cutting disk 20.

Secured to the back of the casing 15 as by screws 29 and extending therebelow is an angle shaped retainer 30 which is substantially the same length 75 as the casing 15. The horizontal leg 31 of this retainer projects forwardly beneath and underlies the lower edge of the casing and the rollers 28. The screws 29 pass through slots 32 in the back portion of the retainer, which slots permit 80 adjustment of the retainer to provide more or less clearance between the leg 31 thereof and the bottom of the casing and which also allow for adjustment to meet variations in size of cutting disks.

The tool and the straight edge are assembled 85 by engaging the leg 31 of the retainer beneath the roller support 12 of the straight edge, at either end of the straight edge, then moving the tool along the straight edge causing the rollers 28 to ride in succession on the top of the support 12. 90 The distance from the back of the knife to the front side of the retainer 30 is very slightly greater than the width of the roller strip so that the tool has limited lateral clearance or play. The depth of the straight edge is such that the knife 20 is 95 normally held just clear of the bottom of the straight edge.

If desired, the rollers 28 may be entirely omitted and the ends of the arms allowed to bear on and slide along the support 12.

100 In using the tool the paper to be trimmed is laid out along the top of the table 33 and the straight edge is laid along the line of the desired cut. Slight downward pressure is then exerted contacting the cutting knife with the paper to be 105 trimmed and transferring the downward pressure through the arms 26 to the straight edge. This movement releases the retainer leg from the underside of the support and allows easy movement of the tool relative thereto. The knife is then 110

moved forward and/or backward along the straight edge cutting the paper along the desired line and in either direction. The straight edge may then be moved to a new position and the cut extended, the trimmed paper shifted along the table, an additional amount unrolled the straight edge positioned, and the operation continued. It will be particularly noted that the pressure on the straight edge is carried by the rollers 28 and 10 that the tool may therefore be easily shifted along the straight edge. It will further be noted that such pressure is directly downward on the straight edge and that this pressure lies entirely within the lateral limits of the straight edge so that irrespective of whether the straight edge is held or not there is no overturning or tendency to overturn it. It will further be noted that the pressure exerted on the straight edge and to the paper which is to be trimmed is directly contiguous to 20 and equally distributed on both sides of the cutting point so that the paper is firmly held in the zone of action of the cutting knife. The cutting knife also is held against the face of the straight edge and caused to move parallel therewith by 25 the retainer 30 so that, irrespective of normal effort, a straight cut along the edge of the straight edge will be made no matter how loosely held or how poorly guided the device may be.

Having described my invention, what I claim is:

30. In a tool of the character described, for use with a straight edge comprising an elongated strip of

sheet metal, having its forward edge extending vertically upward and thence horizontally inward to form a roller support, a recessed casing forming a hand grip, a boss projecting horizontally forward from the back of said casing at the longitudinal center thereof, a vertically disposed cutting disk revolvably mounted on the forward end of said boss, substantially flush with the face of said casing, and extending therebelow, a pair of symmetrically disposed pivot pins projecting horizontally forward from the back of said casing adjacent said boss, arms of equal length, each pivoted on one of said pins and extending longitudinally away from said boss, rollers each mounted on the free end of one of said arms, and adapted to rest on said roller support, an angle shaped retaining member secured to the back of said casing, extending therebelow and having its horizontal leg extending forward beneath said roller support, a spring in said casing urging said rollers downward, against said support and said retaining member upward against the underside of said support, all of said parts being positioned rearwardly of said disk and centered with relation to said grip, whereby downward pressure on said casing will free said retaining member and be centered over and equally borne by said rollers, permitting equal action either forward or backward, and a cover secured to said casing, covering substantially all but the lower edge of said disk. 100

HUGH E. SIMONTON.
